UNITED STATES PATENT OFFICE.

DAVID HEER, OF PHILADELPHIA, PENNSYLVANIA.

DESIGN FOR A BADGE.

SPECIFICATION forming part of Design No. 21,574, dated May 24, 1892.

Application filed April 26, 1892. Serial No. 430,778. Term of patent 7 years.

To all whom it may concern:

Be it known that I, DAVID HEER, a citizen of the United States, and a resident of Philadelphia, Pennsylvania, have invented a new and original Design for a Badge, of which the following is a specification.

My design is fully shown in the accompanying drawing, which represents a front view of the badge.

10 The design comprises the representation A of an oblong upright buckle or loop, through which is drawn a short ribbon B, having three parallel horizontal stripes a b d. Depending from the loop or buckle A is a circular medal 15 D, and surrounding but free from contact with the latter is a ring F, which has alternate segments of different colors.

The essential features of the design are the representation of the buckle or loop, the ribbon with its three stripes, and the depending 20 medal.

I claim—

The design for a badge, having the essential features described and shown in the accompanying drawing.

25 In testimony whereof I have signed my name to this specification in the presence of two subscribing witnesses.

DAVID HEER.
